UNITED STATES PATENT OFFICE.

JOHN AUSTIN, OF FLORISSANT, COLORADO.

WAGON-STARTER.

SPECIFICATION forming part of Letters Patent No. 780,469, dated January 17, 1905.

Application filed March 25, 1904. Serial No. 200,024.

To all whom it may concern:

Be it known that I, JOHN AUSTIN, a citizen of the United States, residing at Florissant, in the county of Teller and State of Colorado, have invented certain new and useful Improvements in Wagon-Starters; and I do hereby declare the following to be a full, clear, and exact description of the invention, such as will enable others skilled in the art to which it app-
10 pertains to make and use the same.

This invention relates to improvements in wagon-gears, and more particularly to means for imparting an initial movement to the wheels of a running-gear.

15 It has heretofore been proposed to start the running-gear of a wagon by applying the pulling pressure directly to the wheels through mechanism engaging the hubs of the wheels; and one object of the present invention is the provision of means for applying the starting draft to the periphery of the wheels instead of to the hubs thereof, whereby a maximum leverage may be obtained.

With this and further objects in view the invention comprises certain novel constructions, combinations, and arrangements of parts, as will be hereinafter fully described and claimed.

In the accompanying drawings, Figure 1 represents a top plan view of a wagon embodying the features of the present invention. Fig. 2 represents a view in side elevation thereof. Fig. 3 represents an enlarged detail fragmentary side elevation of a portion of one 35 of the operating-chains applied and its spring-support. Fig. 4 represents an enlarged detail longitudinal vertical central section taken through the doubletree connections and surrounding parts, parts being illustrated in elevation. Fig. 5 represents a top plan view of the parts disclosed in Fig. 4. Fig. 6 represents a view in side elevation of the parts seen in Fig. 5, the doubletree and parts connected therewith being illustrated in their rear position.

In carrying out the present invention I secure a suitable bracket 1 to each side of the wagon-body 2 or to the vertical standards 3 at each side of the running-gear of the wagon, 45 and each of said brackets carries a suitable

spring 4, supporting the end of a starting-chain 5. The starting-chains 5 extend approximately parallel to each other and are connected at their front ends to the respective opposite ends of the doubletree 6, supported and carried by a tongue 7 in a manner hereinafter fully set forth. Each starting-chain 5 is provided at its rear end with a branch 8, adapted to be wrapped about the felly and tire of the respective rear wheel of the wagon. A 60 branch chain 10, similar to branch 8, is carried by each chain 5 intermediate the length thereof and is adapted to be secured to the felly and tire of the respective front wheel 11 of the wagon. In operation the branch 8 or 65 10, as the case may be, is secured to its respective wheel by interlacing of the links in such manner as to cause the chain to grip the felly and tire so long as the respective chain 5 is under a strain; but as soon as the chain is 70 slackened the lap of the branch chain is released and the branch permitted to drop away from the wheel, the respective spring 4 serving to elevate the given chain 5 for preventing entanglement of the branches thereof with the 75 respective wheels of the wagon. The branch chain in practice is wrapped about the felly and tire of the wheel after the manner indicated in Fig. 3, and the free end of the branch chain is forced beneath one of the loops 80 of the chain, so that strain upon the chain is designed to cause tightening of the laps and slackening of the chain will effect a release thereof.

A bracket 12 is fixed to the tongue 7 near the rear end thereof, and a bracket 13 is spaced forwardly of the tongue and fixed thereto, said brackets carrying a rod 14, arranged parallel to and spaced above said tongue, said rod 14 being secured in place by suitable bolts 15. 85 A collar 16 surrounds the rod 14 and is provided with suitable set-screws 17 17, adapted to be threaded against the same and retaining the collar 16 in a fixed position with respect to the rod 14. Suitable hooks 18 18 project laterally from the collar 17 and are adapted for purposes hereinafter mentioned. A sleeve 19 surrounds the rod 14 and is spaced in the rear of collar 16, a coiled spring 20 being interposed between said sleeve and collar and 90 95 100

surrounding the rod 14, one end of the spring 20 being preferably fixed to the collar 16. Suitable set-screws 21 are carried by the sleeve 19 and are designed to be threaded into 5 clamping contact with the rod 14 for retaining the sleeve in a fixed position relative to said rod. Suitable straps 26 extend upwardly at each side of sleeve 19, and at their upper free ends said straps carry a plate 22, constituting 10 a clevis. The doubletree 6 extends between the plate 22 and the sleeve 19, and a pin 23 extends through the plate 22 through doubletree 6, and is threaded into a sleeve 19 for securing the doubletree 6 in position. The 15 threaded aperture in the sleeve 19, designed to receive the pin 23, extends through the sleeve 19 and permits contact of the pin 23 with the rod 14, whereby said pin may be threaded down into clamping contact with said rod for 20 assisting the set-screws 21 in locking sleeve 19 in position. An extension 24 projects rearwardly from the upper surface of the sleeve 19 and forms a bearing-support for the doubletree 6, plates 25 being preferably secured at 25 the opposite sides of the tongue 7 for forming further supports for the doubletree 6. A bolt 27 connects the straps 26, at the opposite ends of which may be connected suitable chains 28 28, having their lower ends attached to a bolt 30 29, extending through the tongue 7, where- 35 by after the starting operation the strain may be taken up by the chains 28 and bolt 29.

In operation when the wagon is being drawn and the present improved starting devices are 35 not being used the parts are preferably positioned as indicated in Figs. 4 and 5, with chains 28 connecting bolt 27 with bolt 29, or said chains may be removed from bolt 27 and connected to the hooks 18, so that the strain will 40 still be taken up by said chains, but with the cushioning effect of the spring 20, the draft of the load being accomplished through the doubletree 6, sleeve 19, spring 20, collar 16, hooks 18, chains 28, bolt 29, and tongue 7. 45 It will of course be seen that when it is desired to secure the cushioning effect of the spring 20 it is necessary to release the clamping action of the set-screws 21 and of the pin 23.

When it is desired to start a wagon provided with the present improved mechanism, 50 assuming that it is desired to make the start from the two rear wheels, the branches 8 are looped about the felloes and tires of the respective wheels in the manner above described 55 and commonly known as a "cat's-paw," the doubletree 6 having been placed at the rear end of rod 14, as indicated in Fig. 6, and the chains 28 removed for permitting free longitudinal movement of the sleeve 19. When 60 the parts are in this position, the draft-animals are started, and the doubletree 6 is given probably ten to fifteen inches free play, which permits a direct draft on the periphery of the respective rear wheels, causing the

same to rotate, and thereby start the movement of the wagon. As soon as the wheels have been started and the starting-chains 5 are caused to assume a slackened position by the movement of the wheels the cat's-paws will be released and the branch chains 8 permitted 70 to fall free from the wheels, the springs 4 elevating the chains out of the path of the wheels. If it is desired to start the wagon by actuating one rear wheel and one front wheel, it is only necessary to apply the proper branch 75 chains, as above described, or, if desired, all of the wheels may be started simultaneously by applying all of the branch chains. As the start is effected through the forward movement of the doubletree 6, the sleeve 19 travels 80 forwardly on the rod 14 and eventually comes in contact with the cushioning-spring 20, and the impact of said sleeve is taken up by said cushion. It will be observed that the set-screws 17 may be manipulated for facilitating 85 adjustment of the collar 16 longitudinally of the rod 14 for increasing or decreasing the length of stroke of the sleeve 19.

While I have described each of the elements 5 as a "chain" and its branches as "chains," it 90 will be observed that any suitable cables or other flexible means may be substituted for the chains, and I wish it decidedly understood that this substitution is clearly within the scope of the present invention, and I furthermore desire my claims to be construed broadly in the employment of the term "chain" as meaning any flexible means capable of accomplishing the same result attainable with a chain or cable. Furthermore, it will be observed that the starting-chains 5 may be omitted and rods substituted therefor, such as are illustrated in connection with United States Letters Patent No. 695,780, issued to me on the 18th day of March, 1902. It 105 will therefore be seen that it is fully within the scope of the present invention to substitute rods for the chains 5 as long as suitable means are connected with such rods for permitting detachable attachment to the wheels 110 of the wagon.

The tongue-support of some wagons is arranged on top of the tongue, and thus interferes to a certain extent with the backward movement of the doubletree, and sometimes 115 the hounds interfere, and in such instances I contemplate placing the slide well to the front, so as to give the parts ample room for the necessary movement, and when the start has been made ordinary draft may be secured 120 by tightening the set-screws 21 and pin 23 and positioning the chains 28.

Having thus fully described my invention, what I claim as new, and desire to secure by Letters Patent, is—

1. In a wagon-starter, the combination with a wagon, of a starting-chain arranged at one side thereof, a spring engaging the free end

- of said chain, and a branch chain depending from said chain intermediate the length thereof.
2. In a wagon-starter, the combination with a wagon, of a starting-chain connected to the draft mechanism thereof, means for supporting said chain, and a plurality of branches carried by said chain.
3. In a wagon-starter, the combination with a wagon, of a starting-chain connected with the draft mechanism thereof, means for supporting said chain, said chain extending longitudinally of the body of said wagon past the supporting-wheels thereof, and a plurality of branch chains carried by said starting-chain, one branch chain being arranged contiguous each of the wheels of said wagon.
4. In a wagon-starter, the combination with a wagon, of a starting-chain connected to the draft mechanism thereof, a spring supporting said chain, and means for detachably connecting said chain to one of the wheels of said wagon.
5. In a wagon-starter, the combination with a wagon, of a chain extending longitudinally of the body thereof and connected to the draft mechanism of said wagon, a spring supporting the rear end of said chain, and wheel-engaging means carried by said chain.
6. In a wagon-starter, the combination with a wagon, of a starting means extending longitudinally of the body of said wagon, a spring supporting the rear end of said starting means, and branch chain for detachably securing said starting means to one of the wheels of said wagon.
7. In a wagon-starter, the combination with a wagon and tongue therefor, of a rod spaced above said tongue, means securing said rod to said tongue, doubletree-carrying means movably arranged on said rod, a doubletree carried thereby, means for securing said doubletree-carrying means against movement independently of said rod, and wagon-starting means connected to said doubletree.
8. In a wagon-starter, the combination with a wagon and tongue therefor, of a rod spaced above said tongue, a sleeve slidably mounted on said rod, a doubletree carried by said sleeve, means for locking said sleeve against movement on said rod, connections between said sleeve and said tongue adapted to relieve the strain on said rod, and starting means connected to said doubletree.
9. In a wagon-starter, the combination with a wagon and tongue, of a rod spaced from and connected to said tongue, a sleeve slidably surrounding said rod, a collar surrounding said rod and spaced from said sleeve, cushioning means interposed between the said collar and sleeve, means for locking said collar against movement independently of said rod, a doubletree carried by said sleeve, and starting means connected with said doubletree.
10. In a wagon-starter, the combination with a wagon and a tongue therefor, of a rod spaced from said tongue and connected thereto, a sleeve slidably carried by said rod, a setscrew carried by said sleeve and adapted to engage said rod for locking said sleeve against movement independently of the rod, a collar surrounding said rod, means for retaining said collar against movement independently of the rod, a spring interposed between said collar and sleeve, and wagon-starting means connected with said sleeve.
11. In a wagon-starter, the combination with a wagon and a tongue therefor, of starting means carried by said tongue, and a stop adjustable longitudinally of said tongue and designed to control the length of stroke of said starting means.
12. In a wagon-starter, the combination with a wagon and tongue therefor, of starting means carried by said tongue, and an adjustable cushion adapted to control the length of stroke of said starting means.
13. In a wagon-starter, the combination with a wagon and tongue connected thereto, of a rod spaced from said tongue, starting means carried by said rod, and a collar adjustably carried by said rod in the path of movement of said starting means.
14. In a wagon-starter, the combination with a wagon and tongue therefor, of a rod spaced from and connected to said tongue, starting means carried by said rod, an adjustable stop carried by said rod, and a spring retained in the path of movement of said starting means by said stop.
15. In a wagon-starter, the combination with a wagon and tongue therefor, of a rod carried by and spaced from said tongue, starting means carried by said rod, and an adjustable cushioned stop arranged in the path of movement of said starting means and adapted to be adjusted for controlling the length of stroke of said starting means.

In testimony whereof I hereunto affix my signature in presence of two witnesses.

JOHN AUSTIN.
